APPARATUS FOR PUMPING WELLS

Frederick Edmund Scheider and James Carl Hinkle, Los Angeles, Calif.; said Hinkle assignor to said Scheider

Refiled for abandoned application Serial No. 55,968, December 24, 1935. This application June 15, 1937, Serial No. 148,364

2 Claims. (Cl. 103—44)

An object of this invention is to provide an efficient apparatus for pumping wells particularly deep wells such as oil wells. This application is a duplicate of, and is refiled for abandoned application Serial Number 55,968.

In wells of great depth, the utilization of the conventional forms of pumping equipment has reached, and in many instances exceeded the limit of economical and efficient use and it is therefore an object of this invention to provide an apparatus whereby wells, regardless of great depth, may be economically and efficiently pumped.

Another object is to provide a reliable and efficient apparatus for pumping wells wherein the use of sucker rod equipment is inefficient, costly and not infrequently impossible.

A further object is to provide an apparatus of the character described which utilizes the inherent forces of the well to function in the pumping operation and thereby reduce pumping costs and increase production.

A further object of the invention is to eliminate the use of sucker rods in well pumping equipment.

With the above and other objects in view the invention consists in the novel combination of parts hereinafter described, illustrated in the accompanying drawing, and set forth in the claims hereto appended, it being understood that various changes in form, proportion, size and minor details of construction within the scope of the claims may be resorted to without departing from the spirit or sacrificing any of the advantages of the invention.

Referring to the drawing:

Figure 1 is a fragmentary vertical sectional view of a well exemplifying one embodiment of the invention.

Figure 2 is a reduced cross sectional view on line 2—2 of Figure 1.

Figure 3 is a reduced cross sectional view on line 3—3 of Figure 1.

Figure 4 is a vertical sectional view showing a variational form of the invention.

In carrying out one embodiment of the present invention, independent liquid columns capable of counterbalancing one another are created in the well to be pumped either by providing partitioned or divided pipe lines or by utilizing independent pipe lines within the well casing or by any suitable means. Next, the columns are interactively connected so that a counterbalancing force derived from the hydrostatic equilibrium of the liquid in said columns is interactively applied from one to the other of the columns. This procedure creates substantially counterbalanced

liquid columns in a well, a factor making the elimination of sucker rods possible as well as providing for a less expensive and more efficient pumping of wells regardless of the depth thereof.

The interactive connection of the two columns 5 may be provided through the medium of suitably valved plungers, or by any other means which will transmit from one column to the other the counterbalancing force of said columns while, however, maintaining said columns independent. 10

The next step is that of alternately applying a pumping power increment to the liquid columns, which increment alternately coacts with the respective counterbalancing forces of the columns and causes first one and then the other to be depressed whereupon first one and then the other of the columns will be raised sufficiently to cause the liquid to flow out of the top of the well. 15

This step may be accomplished by alternately applying to the tops of said liquid columns a force from alternately actuated power plungers or rams whereby to depress one column and raise the other and vice versa as aforesaid. 20

Inasmuch as the forces of equilibrium of the two liquid columns function in the pumping operation; but a relatively small power increment is required to cause the liquid columns to flow from the top of the well. 25

As here shown the apparatus comprises a well 1 comprised of the well casing 2 in which is 30 mounted a pipe line 3 embracing the liquid column 4. Within the line 3 is a pipe line 5 embracing the liquid column 6. Both of the pipe lines 3 and 5 illustrated as forming the independent liquid columns 4 and 6 extend the entire depth of the well. The lower end of the pipe line 5 terminates in the plunger barrel 7 of sufficient length to provide the plunger stroke desired. The pipe line 3 terminates in the casing or barrel 8. The plunger barrel 7 is positioned and secured off-center, Figure 2, in the casing 8 for the purpose of accommodating, in small bore apparatus, the several valved ports later described. The lower end of the casing 8 is disclosed as at 9 with relation to the plunger barrel 7. 35

Within the plunger barrel 7 is fixed the partition 10 through and in which the tubular plunger rod 11 is slidably mounted. The upper end of the rod 11 is provided with the piston or plunger head 12 operating in the upper portion 50 of the barrel 7 against the liquid column 6, there being an opening 13 through the plunger 12 to the bore of the plunger rod 11 which opening is controlled by the upwardly opening check valve 14.

At its lower end and within the extension 15 55

of the plunger barrel 7, the extension 15 being of such bore as to provide the ratios of plunger head areas requisite or desired, the tubular rod or plunger 11 constitutes or carries the plunger head 16. Port openings 17 communicate with the bore 18 controlled by the check valve 14 in plunger head 12. The extension or plunger barrel 15 is provided with the liquid inlet opening 19 communicating with the well supply and controlled by the inwardly opening check valve 20 and the outlet openings 21 communicating with the liquid column 4 which freely surrounds the plunger barrels 7 and 15. The outlet openings 21 are controlled by the outwardly opening check valves 22. Below the partition 10 the plunger barrel is provided with the inlet openings 23 forming a sealed passage through the liquid column 4 and communicating with the well liquid supply, admission of which to the plunger barrel is controlled by the inwardly opening check valves 24. Above the partition 10 and below the plunger head 12, when the latter is in its lowermost stroke position, the plunger barrel is provided with the openings or ports 25 freely permitting the liquid of the liquid column 4 to have inlet and outlet flow relative to the movement of the plunger head 12 in relation to the fixed partition 10.

The tops of the pipe lines 3 and 5 forming the liquid columns 4 and 6 are closed as at 26 and 27 with the exception of the vent valves 28 and 29 and the pipe line connections 30 and 31 for connection of the liquid column actuating power source. In simple form, a power operated plunger or ram 32 is connected with the upper end of line 3 and a similar power unit 33 is connected to the upper end of line 5. These power units are synchronously driven by any suitable means of power application not shown. The power units 32 and 33 are provided with the outlets 34 and 35 through which liquid flows or is pumped from the well and by means of which the entire system may be primed or charged with liquid.

That portion of the plunger barrel below the fixed portion 10 is divided by the plunger head 16 into the chambers A and B whereby the apparatus is of the double action type wherein discharge of the liquid to be pumped occurs on each stroke of the piston.

Operation is as follows:

Upon lowering the apparatus into the well with the parts in the position shown in Figure 1, liquid from the well supply enters chamber A through the valved ports 23. The pipe lines 3 and 5 and the power units 32 and 33 are primed or filled through the respective outlets 34 and 35 with liquid such as that of the well supply or otherwise, and the apparatus is ready for starting.

The power unit 32 is now operated to exert a pumping power increment on the liquid in column 4 and this column now flows through the ports 25 and acts upon the plunger head 12 causing the plunger ensemble parts C to rise whereby the liquid from the well supply in chamber A, closed to the well supply by the check valves 24, is caused to flow through the ports 17 bore 18 and raise the check valve 14; and, upon continued rising of the plunger, is caused to flow into the liquid column 6 during the full upstroke of the plunger head 12 caused by the relative movement of the ram 32. Upon the initial upflow of the liquid in column 6 the ram 33 is retracted to the position, shown in dotted lines, exposing the outlet 35 through which the stroke volume of the chamber A flows from the well. Simultaneously,

during the upstroke of the plunger C, liquid from well supply enters chamber B through the inlet valved port 19.

The pumping power increment is now applied to the ram 33 causing the liquid therein to flow into the column 6 whereupon the plunger C is caused to make the down stroke. During this down stroke the liquid of column 4, caused by the ram 32 to flow through the ports 25 to raise the plunger C, is now caused by the ram 33 to flow out through the ports 25 into the liquid column 4 and in addition causes the liquid in the chamber B, closed to the well supply by the check valve 20, to flow through the outwardly opening check valves 22 into the column 4. Upon the initial upflow of the liquid in column 4, the ram 32 is retracted to the position shown thereby exposing the outlet 34 through which the stroke volume of chamber B flows from the well. The movements described constitute a pumping cycle continuous of which will pump the well.

It will now be apparent that the plunger ensemble C is interactive between the lower "ends" of the liquid columns 4 and 6 and exercises from one liquid column to the other the forces of hydrostatic equilibrium and in addition exerts upon either liquid column, when stationary or while moving, any force applied to the other, while concurrently maintaining the independence of the liquid columns.

It should be noted that the stroke of the plunger ensemble C may be determined and regulated by the stroke of the rams 34 and 35.

The embodiment of the invention shown in Figure 4 operates under counterbalanced liquid columns E and F having pressure applied thereto alternately in the same manner as in the previously described form of the invention. The plunger head 40 at the top of the plunger 41 is exposed to the lower end of column F whereas the lower side of said plunger head is exposed through the openings 42 to the other column E whereby the plunger is effective to transmit the interactive force of said columns from one to the other thereof while maintaining said columns independent of one another.

The plunger barrel 43 in which the plunger 41 operates has a valved intake opening 44, communicating with the supply of liquid in the well, and is also provided with the valved outlet opening 45 communicating with the liquid column E. On the upstroke of the plunger liquid flows through the intake 44 into the barrel 43 whereas on the down stroke of said plunger the intake 44 is closed and the liquid is caused to flow out of the plunger barrel 43 through the valved outlet 45 into column E which therefore rises until the liquid thereof flows out of the top of the well.

We claim:

1. In well pumping apparatus, a well including independent pipe lines arranged one within the other and containing liquid columns which are capable of substantially counterbalancing one another, a power operated means for alternately applying pressure to the top of said liquid columns, a plunger ensemble operative adjacent to the lower ends of said pipe lines to separate said liquid columns and to transmit the forces of said columns from one to the other thereof, a plunger barrel contiguous with the lower end of the inner pipe line, a partition dividing said barrel into upper and lower sections, said plunger ensemble including a tubular plunger rod slidable in said partition, a plunger head on the upper end of said rod having a port therethrough

- communicating with the bore of said tubular rod, an upwardly opening check valve controlling said port, a plunger head on the lower end of said rod, said tubular rod having an opening in 5 its lower end above the lowermost plunger head communicating with the lower section of said barrel, said barrel having an open port above the partition and below the upper plunger head when the latter is in its lowermost position, a liquid 10 intake member for said barrel located below the partition and communicating the supply of well liquid with the portion of the lower barrel section located above the lower plunger head, an inwardly opening check valve controlling said intake 15 member, said barrel having an outlet port opening into the outer pipe line from the portion of the barrel located below the lower plunger head, an outwardly opening check valve controlling said outlet opening, means closing the lower end 20 of the outer pipe line, said barrel having a liquid intake opening at its lower end communicating with the supply of liquid in said well and an upwardly opening check valve controlling the last named opening.
- 25 2. In well pumping apparatus a well including independent pipe lines containing liquid columns, a power operated means for alternately applying pressure to the tops of said liquid columns, a plunger means operative in said pipe lines to separate said liquid columns and to transmit the forces of said columns from one to the other thereof, a plunger barrel contiguous with the lower end of one pipe line, a partition dividing said barrel into upper and lower sections, said 5 plunger means including a tubular plunger rod slideable in said partition, a plunger head on the upper end of said rod, a plunger head on the lower end of said rod, said plunger rod having an opening therein at its lower end and an opening at 10 its upper end which latter communicates with the barrel space above the upper plunger head, a valve controlling the last named opening, said barrel having an open port above the partition, a liquid intake member located between the low- 15 ermost plunger head and said partition and communicating with the supply of liquid in said well, an inwardly opening check valve controlling said intake member, said barrel having an outlet port opening into one pipe line from the portion of the barrel located below the lower plunger head, an outwardly opening check valve controlling said outlet opening, means closing the lower ends of 20 said pipe lines and providing an intake communicating the lower end of the barrel with the supply of liquid in said well, and an upwardly 25 opening check valve controlling said intake.
